THOMAS KEPPEL NORTH, OF WESTMINSTER, LONDON, ENGLAND, ASSIGNOR TO VICKERS
LIMITED, OF WESTMINSTER, ENGLAND.

SUBMARINE MINE.

1,299,601.

Specification of Letters Patent.

Patented Apr. 8, 1919.

Application filed July 2, 1917. Serial No. 178,247.

To all whom it may concern:

Be it known that I, THOMAS KEPPEL NORTH, a subject of the King of Great Britain, residing at Vickers House, Broad-
5 way, Westminster, in the county of London, England, have invented certain new and useful Improvements in or Relating to Submarine Mines, of which the following is a specification.

10 This invention relates to submarine mines of the kind provided with means for automatically causing the flotation chamber or mine proper to be anchored at a predetermined depth beneath the surface of the water.

15 According to the invention I so construct and arrange the parts of the mine that when launched the mine will sink as a single unit until it reaches the sea bed, whereupon,

20 after the lapse of a certain interval of time, the flotation chamber will rise toward the surface of the water and subsequently be drawn downward to assume a predetermined depth below the surface. For this
25 purpose the mine may comprise three main parts or elements, viz: a flotation chamber containing the explosive charge, an anchor, and a sinker. At the time of launching, the sinker is of a weight sufficient to overcome
30 the combined buoyancy of the flotation chamber and the anchor; and the anchor is of the kind that has a varying buoyancy, that is to say it is made hollow so that on launching it possesses buoyancy but sub-
35 sequently loses its buoyancy by having water admitted to it either by a slow leakage or by the opening of a water inlet port controlled by the flotation chamber. Inter-
40 posed between the sinker and the anchor is a cable or chain (hereinafter termed the sinker cable) whose effective length corre-
45 sponds to the depth to which the flotation chamber will be anchored beneath the sur-
50 face of the water, and interposed between
55 the anchor and the flotation chamber is an-
other cable or chain (hereinafter termed the anchor cable) which, when the flotation chamber rises toward the surface, is paid
60 out from the anchor preferably against the
65 resistance or friction of a suitable brake.
70 The flotation chamber is normally locked
75 to the anchor and the latter is detachably
80 connected to the sinker, so that at the time
85 of launching, these parts constitute a single
90 unit and sink to the sea bed in that condi-
95 tion. After the lapse of a suitable interval
100 of time, the anchor is released from the
sinker and together with the flotation chamber to which at this time it is locked, floats
upward until arrested by the sinker cable. 60
When this cable becomes taut the anchor is
automatically released from the flotation
chamber and the latter is permitted to raise
toward the surface of the water by the pay-
ing out of the anchor cable. During this 65
time the sinker cable continues in its taut
condition, but when the flotation chamber
emerges from the water and momentarily
loses its buoyancy, the tension on the sinker
cable diminishes and thus permits suitable 70
means to become operative for preventing
further paying out of the anchor cable. Sea
water is then allowed to enter the hollow
anchor so that after a short interval of time
the weight of the anchor is increased suffi- 75
ciently to overcome the buoyancy of the flota-
tion chamber and sink, thereby drawing the
latter beneath the surface of the water until
the anchor rests on the sea bed; that is to
say the flotation chamber will at this time 80
have assumed a depth predetermined by the
effective length of the sinker cable and will
be anchored at that depth.

In order that the said invention may be clearly understood and readily carried into effect the same will be more fully described with reference to the accompanying drawings, in which:

Figures 1 to 6 illustrate diagrammatically various positions of the mine after being launched and finally coming to anchor with the flotation chamber at a predetermined depth beneath the surface of the water.

Figs. 7 and 7^a show a longitudinal sec-
90 tion of the mine showing the general ar-
95 rangement and construction of the internal
parts according to the preferred embodi-
ment of the invention. It will be under-
stood that in this figure owing to want of
space on the sheet the mine has been sepa-
100 rated into two parts along the line X X
one being shown on Sheet 2 and the other

on Sheet 3 and that these two parts are actually disposed end to end and constitute one piece; also that parts of the mine have been removed at the lines Y Y and Z Z.

- 5 A is the mine body or flotation chamber which contains within the casing A^x the explosive charge. B is the hollow anchor and C is the sinker. E is the sinker cable and F is the anchor cable. Fig. 1 shows the parts 10 A, B and C as a connected whole or single unit after the mine has been launched and has reached the sea bed, the anchor B being at such time located within the sinker C. The anchor may be locked to the sinker by means 15 of a device of the slow releasing or delayed action type such as a dash-pot contrivance or a plug of soluble salt, and for locking the flotation chamber to the anchor a mechanically releasable coupling device is employed. 20 Fig. 2 shows the position of the parts just after the flotation chamber A and anchor B, still locked together, have been released from the sinker C and the sinker cable E has commenced to pay out under the upward pull 25 due to the combined buoyancy of the flotation chamber and hollow anchor. Fig. 3 shows the position of the parts after the sinker cable E has become taut and the flotation chamber A has been released from the 30 anchor B, the anchor cable F having just commenced to pay out from the anchor B. When the sinker cable E becomes taut, the coupling device connecting the flotation chamber A to the anchor B is released and 35 the anchor cable F is paid out from the anchor against the resistance or friction of a brake. Fig. 4 shows the position of the parts when the flotation chamber by its buoyancy reaches and emerges from the surface of 40 the water, both the sinker cable E and the anchor cable F being taut. As the mine emerges from the water the tension on the sinker cable E diminishes, as shown in Fig. 45 5, thereby allowing a suitable locking device to come into action to prevent further paying out of the anchor cable F. At the same time the interior of the anchor B is placed in 50 communication with the external water, thereby allowing the latter to enter the said anchor B. Following on the entry of the water into the anchor the additional weight 55 thereby imparted to the anchor causes it to sink and pull the flotation chamber beneath the surface of the water until, as shown in Fig. 6, the anchor reaches the sea bed and the flotation chamber arrives at its predetermined depth of immersion.

I will now describe the constructional form of the mine and its internal mechanism for 60 causing the separation of the parts in the manner above explained with reference to Figs. 1 to 6, for which purpose reference will be had to Fig. 7, it being understood that the parts shown by this figure are shown only by 65 way of example and that I do not intend my

invention to be limited thereto. In this figure the parts are shown in the position they occupy prior to the launching of the mine. The sinker C is constituted by a long cylindrical casing open at one end and containing 70 the hollow anchor B which is also of cylindrical form, the said open end receiving the contiguous end of the flotation chamber A which is likewise of cylindrical form. In the example shown the anchor 75 B is detachably locked to the sinker C by means of a delayed action device H which is in the form of a dash-pot and comprises a cylinder H' attached by means of a screw threaded part H² to the base of the anchor B, and a piston H⁴ having a rod H⁵ connected by a transverse pin H⁶ to the sinker C. The cylinder H' has an enlarged portion H⁸ near its outer end and the piston is detachably connected to the piston rod by means of 80 a detent pin H⁷ having a conical or hemispherical end which engages a similarly shaped circumferential groove H⁹ in the piston rod. When the mine is launched (prior to which a safety screw G carried by the 85 sinker is disengaged from a flange G' on the anchor) and reaches the sea bed, the tendency of the flotation chamber and the anchor to move upward under the influence of their buoyancy against the resistance of the sinker 90 will cause relative movement between the cylinder H' and the piston H⁴ with the result that the piston will move slowly down the cylinder H' compressing the heavy oil beneath it, until the detent pin H⁷ reaches 95 the enlarged portion H⁸ of the cylinder, whereupon the said pin H⁷ will become disengaged from the piston rod H⁵ and release the latter, thus rendering the flotation chamber and anchor free to rise and leaving the 100 sinker on the sea bed.

The sinker cable E (which is a chain in the example shown) is secured at one end to the sinker and at the other end to a shackle hook I connected to the lower end 11 of a spring controlled rod J the length of this cable determining the eventual depth below the surface of the water, which the flotation chamber will assume when finally anchored. The said rod J extends axially 1 through the anchor B and its upper conical end J' abuts against and holds fast the coupling device that detachably locks the flotation chamber to the anchor as will be hereinafter described. The anchored cable 1 F is wound around the cylindrical exterior surface of the hollow anchor B which is composed of a cylindrical casing closed at its ends by plates B', B² formed with bosses B³, B⁴ through which the spring controlled 1 rod J extends. The plate B' has a water inlet opening L⁴ which is normally kept closed so that water cannot enter the hollow anchor until the proper time. Above the upper plate B' is a loose disk or circular plate K 1

which is so mounted that relative rotary movement can take place between these parts, the said loose disk K carrying a braking device L and being formed with an aperture or eye L' through which the anchor cable F passes. The said loose disk K is also formed with a circular opening L² for co-operating with a spring plunger M' and it is also formed with an opening L³ for uncovering the water inlet opening L⁴. The braking device L comprises a plunger L^x which is pressed by means of a spring L⁵ into contact with the surface of the upper end plate B' of the anchor. The pressure exerted by the plunger L^x is capable of adjustment by means of a screw threaded nut L⁶. Mounted within a depending chamber M in the upper end plate B', is the plunger M' which tends to move upward by the action of a spring M². In the side of this plunger is a longitudinal slot M⁴ terminating in recesses M⁶, M⁸ with which co-operates one end of a transverse rod M' the other end passing through an opening in the boss B³ of the end plate B' and abutting against the spring controlled rod J. N is a flanged member which is carried by the boss B³ and surrounds the upper part of the rod J and serves to retain the loose disk K on the end plate B', the said flanged member being held in place by a screw I' carried by the end plate B' and engaging with a circular groove I² in the said flanged member. Square faces J², J² are provided on the rod J to prevent it rotating relatively to the anchor B. During the paying out of the anchor cable F relative movement can take place between the disk K and the anchor under the control of the spring brake L. The upper end of the anchor cable is connected to a shackle F' pivotally mounted in a boss O at the base of the flotation chamber A to which boss is also screwed or otherwise secured the end of a rod O' forming part of the firing gear and surrounded by the striker spring O⁶ and carrying the striker head O² as will be hereinafter more fully described. Mounted within the aforesaid flanged member N are radially displaceable detents N² having beveled or chamfered ends and elongated grooves N⁸ with which engage screws N⁴ carried by the flanged member N. Connected to the lower end of the flotation chamber are hooked members P', the free ends of which engage the outer ends of the detents N² and thereby lock the anchor to the flotation chamber. The rod J is formed with a circumferential groove J⁸ and is provided with a sleeve J⁴ connected to the rod J and having at its upper end a collar J⁶ between which and the boss B⁴ of the lower end plate B², is a helical spring J⁶. On the anchor B and the flotation chamber A rising by their buoyancy clear of the

sinker C and the sinker cable E being rendered taut, the rod J is retracted thereby compressing the spring J⁶ and bringing the conical end J' of said rod opposite the detents N² which are then free to move inwardly. The upward pull of the flotation chamber then causes the hooked members P' to force inward the detents N² and unlock the connection between the anchor and the flotation chamber. The flotation chamber then rises by its buoyancy, unwinding the anchor cable F as it ascends, relative rotary movement at the same time taking place between the disk K and the anchor, against the resistance of the brake L. When the flotation chamber reaches and emerges from the surface of the water and rebounds, the tension on the sinker cable E diminishes and permits the compressed spring J⁶ to re-act and force the rod J upward until the groove J⁸ comes opposite the inner end of the rod M' and renders the latter free to move radially inward. By the relative rotary movement between the disk K and the anchor, the opening L² will come opposite the end of the plunger M', when the inner end of the rod M' will be forced into the groove J⁸ and the plunger M' will then move upward under the influence of its spring M² until the recess M⁶ in the lower end of its slot M⁴ is engaged by the outer end of the rod M'. The plunger M' being now in engagement with the opening L² any further unwinding of the anchor cable is prevented owing to the relative rotary movement between the disk K and the anchor being stopped. The water inlet opening L⁴ in the end plate B' of the anchor will in the meantime be maintained uncovered by the opening L³ in the disk K coming opposite thereto, thus allowing the water to flow into and sink the anchor B, which in its descent will draw the flotation chamber A downward to the desired depth of immersion. The water inlet opening L⁴ may be closed if desired by a soluble or automatically detachable plug.

There is provided around the upper end of the flotation chamber A, a number of (say three) contact members Q which when in their operative condition are adapted to be struck by a passing ship in order to fire the mine. Each contact member comprises in the example shown a fixed cylindrical casing Q' located within the flotation chamber and containing an inner spring controlled part Q² and an outer part Q³, which parts up to the moment of launching the mine are held within the casing Q' by a mechanical safety device R and a hand safety device R² co-operating with an annular head or flange R' on the inner part Q². The outer part Q³ is attached to the casing Q' by a shearable screw Q⁴ which also engages and holds in position a plain cylindrical pin Q⁵ located

within the base of the casing Q' and having a head Q^6 . The mechanical safety device R comprises a split pin which engages openings in a flange R^3 of the casing Q' and 5 extends across the face of the annular flange R' of the inner part Q^2 . The hand safety device comprises a wedge piece which is inserted into the split portion of the aforesaid pin of the mechanical safety device, the said 10 wedge piece being adapted to be withdrawn from the pin by means of the handle and cord S prior to the launching of the mine. The split pin is connected by means of a cord S' to a catch S^2 on the sinker so that in 15 the separation of the flotation chamber from the sinker the aforesaid split pin R is automatically withdrawn. The inner part Q^2 then moves outward under the influence of its spring, until a spring controlled pin T 20 engages a recess T' , thus locking the part Q^2 in its extended position. Pivotaly mounted on the inner end of the casing Q' is a bent lever U , one end U' of which engages the head Q^6 of the pin Q^5 . Passing through an 25 eye U^2 in the other end of the lever is a cord or cable U^3 which, after being passed through similar eyes in as many other contact members as may be provided, is finally secured to the last eye of the series. Connected 30 to the other end U^5 of the cord U^3 is an eye U^6 through which passes a second cord V , one end V' of which is attached to a tensioning device (not shown) and the other end of which, after being passed through 35 guiding pieces V^2 and around a grooved pulley P controlling the firing gear, is finally attached to an eye V^3 on the interior of the flotation chamber. In the length of the cable V is a spring V^4 which is placed in a state of 40 tension by the aforesaid tensioning device connected to the cable end V' so that it tends to rotate the pulley P . As long as the spring V^4 remains in a state of tension, the end U^2 of the aforesaid lever U is retained in the 45 position shown in the drawing, being prevented from movement by its other end U' bearing against the head Q^6 of the pin Q^5 . The aforesaid firing gear comprises the connecting rod O' which is connected to the 50 striker head O^2 by radial detents O^4 engaging a recess O^5 in the connecting rod. The striker casing is provided with an enlarged part O^7 so that when the connecting rod and striker head are permitted to be pulled down- 55 wardly against the resistance of the spring O^6 the said detents will move radially outward and disconnect the striker head from the connecting rod, and thus allow the said striker head to fly forward under the influence 60 of the spring to fire the detonator and explode the mine. The connecting rod is normally prevented from downward movement by radial detents O^8 having beveled ends which engage a correspondingly formed

circumferential recess O^9 in the said connecting rod. The detents O^8 are normally held in engagement with the recess O^9 by the aforesaid grooved pulley P . This pulley is formed with radial recesses P^2 shown by dotted lines, which, when the pulley is rotated as above described are brought opposite the outer ends of the detents O^8 so as to permit of their radial displacement and the liberation of the connecting rod O' . W is a diaphragm employed in lieu of the usual type of stuffing box to form a water tight joint. It will be understood that when the mine is in its anchored position with the flotation chamber submerged at the required depth below the surface of the water, there is a constant tendency for the flotation chamber to rise owing to its buoyancy, such rising movement being prevented by the solid part of the pulley P engaging the locking detents O^8 . When, however, one of the protruding contact members Q is struck by a passing ship the lateral strain transmitted by the parts Q^2 , Q^3 to the pin Q^4 shears the latter, thus releasing the pin Q^5 and allowing the lever U to be drawn down about its fulcrum by the tension of the cord U^4 . The pull of the spring V^4 will thus cause the pulley P to perform a partial rotation and bring the recesses P^2 opposite the ends of the detents O^8 . The buoyancy of the flotation chamber and the shape of the detents O^8 will have the effect of forcing the latter into the recesses P^2 and will permit the flotation chamber to rise slightly relatively to the striker and the anchor cable, thereby compressing the spring O^6 as the striker casing moves upward until the detents O^4 come opposite the enlarged part O^7 and release the striker head as aforesaid.

Suitable means may be employed for varying the length of the sinker cable E .

In another constructional form of the mine, instead of the aforesaid delayed action releasing device being interposed between the sinker C and the anchor B it may be interposed between the anchor and the flotation chamber, the anchor being merely connected to the sinker by the sinker cable and not detachably locked thereto as is the case in the construction described with reference to Fig. 7. In this instance the delayed action releasing device may take the place of the aforesaid coupling device that is displaced to release the flotation chamber from the anchor when the sinker cable becomes taut. In this construction, the various operations that occur after the flotation chamber has become released from the anchor, are similar to those described with reference to Fig. 7.

What I claim and desire to secure by Letters Patent of the United States is:

1. A submarine mine comprising a flota-

- tion chamber, means for causing said chamber when launched to sink initially below the depth at which it is to be finally anchored, means for permitting said chamber 5 subsequently to rise toward the surface of the water and means for causing said chamber to be thereafter drawn downward to assume a predetermined depth below the surface.
- 10 2. A submarine mine comprising a flotation chamber, an anchor and a sinker which are adapted when launched to sink as a single unit to the sea bed, a sinker cable interposed between the sinker and the anchor, 15 an anchor cable interposed between the anchor and the flotation chamber, means for causing the anchor and the flotation chamber to separate from the sinker after the mine reaches the sea bed and to rise by their 20 buoyancy to an extent dependent upon the length of said sinker cable, means for causing the flotation chamber to become disengaged from the anchor and to rise by its buoyancy toward the surface under the control of said anchor cable, and means for causing the anchor to subsequently sink to the sea bed so as to draw the flotation chamber a predetermined depth below the surface.
3. A submarine mine comprising a flotation 30 chamber, an anchor, a sinker and cables for connecting these parts, which on launching sink as a single unit to the sea bed, means for subsequently causing said parts to separate so that the flotation chamber rises by its 35 buoyancy toward the surface, said anchor being made hollow to possess initial buoyancy and being provided with means whereby the external water is permitted to enter it as the flotation chamber reaches the surface so as to 40 overcome the buoyancy of the anchor and cause it to sink to the sea bed and draw the flotation chamber a predetermined depth below the surface.
4. A submarine mine comprising a flotation 45 chamber, an anchor and a sinker and cables for connecting these parts which parts on launching sink to the sea bed and subsequently becomes separated from one another to a predetermined extent, and a slow releasing or delayed action device which allows the anchor to separate from the sinker after the parts of the mine have reached the sea bed.
5. A submarine mine comprising a flotation 55 chamber, an anchor and a sinker and cables for connecting these parts which parts on launching sink to the sea bed and subsequently become separated from one another to a predetermined extent, and a slow releasing or delayed action device which allows the flotation chamber to separate from the anchor.
6. A submarine mine comprising a flotation 60 chamber, an anchor possessing initial
- buoyancy, and a sinker which on launching 65 sink to the sea bed and subsequently become separated, a cable interposed between said buoyant anchor and the flotation chamber, paying-out gear for said cable and means for stopping automatically the paying-out 70 of said cable when the flotation chamber reaches the surface.
7. A submarine mine comprising a flotation chamber, an anchor possessing initial buoyancy, and a sinker which on launching 75 sink to the sea bed and subsequently become separated, a cable interposed between said buoyant anchor and said flotation chamber, paying out gear for said cable, means for stopping automatically the paying-out 80 of said cable and means for simultaneously admitting external water to the anchor so as to destroy its buoyancy and cause it to sink to the sea bed.
8. A submarine mine comprising a flotation 85 chamber, means for causing said chamber when launched to sink initially below the depth at which it is to be finally anchored, means for permitting said chamber subsequently to rise toward the surface of 90 the water, means for causing said chamber to be thereafter drawn downward to assume a predetermined depth below the surface, contact members normally positioned within said flotation chamber, and means 95 for causing said contact members to assume their operative position on the flotation chamber rising toward the surface of the water.
9. A submarine mine comprising a flotation 100 chamber, means for causing said chamber when launched to sink initially below the depth at which it is to be finally anchored, means for permitting said chamber subsequently to rise toward the surface of 105 the water, means for causing said chamber to be thereafter drawn downward to assume a predetermined depth below the surface, contact members normally positioned within said flotation chamber, means for causing 110 said contact members to assume their operative position on the flotation chamber rising toward the surface of the water, an explosive charge within said flotation chamber and means adapted to be actuated on contact between said members and a passing ship for firing said explosive charge.
10. A submarine mine comprising a flotation 115 chamber, means for causing said chamber when launched to sink initially below 120 the depth at which it is to be finally anchored, means for permitting said chamber subsequently to rise toward the surface of the water, means for causing said chamber to be thereafter drawn downward to 125 assume a predetermined depth below the surface, contact members normally positioned within said flotation chamber, means

for causing said contact members to assume their operative position on the flotation chamber rising toward the surface of the water, an explosive charge within said flotation chamber, means adapted to be actuated on contact between said members and a passing ship for firing said explosive charge, said means comprising a firing gear,

a tension device normally adapted to retain said firing gear inoperative, said tension device being adapted to be released by the rupture of one or more of said contact members. 10

In testimony whereof I affix my signature.

THOMAS KEPPEL NORTH.
